(57) **CLAIM**

The ornamental design for the compressor, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view on the front side and left hand side of a compressor in accordance with an embodiment of the present invention;

FIG. 2 is a front view of the compressor of FIG. 1;

FIG. 3 is a rear view of the compressor of FIG. 1;

FIG. 4 is a top view of the compressor of FIG. 1;

FIG. 5 is a bottom view of the compressor of FIG. 1;

FIG. 6 is a left hand side view of the of the compressor of FIG. 1;

FIG. 7 is a right hand side view of the compressor of FIG. 1;

FIG. 8 is a perspective view on the front side and left hand side of a compressor in accordance with an embodiment of the present invention that is the same as the embodiment of FIG. 1, other than this embodiment additionally includes color features;

FIG. 9 is a front view of the compressor of FIG. 8;

FIG. 10 is a rear view of the compressor of FIG. 8;

FIG. 11 is a top view of the compressor of FIG. 8;

FIG. 12 is a bottom view of the compressor of FIG. 8;

FIG. 13 is a left hand side view of the of the compressor of FIG. 8;

FIG. 14 is a right hand side view of the compressor of FIG. 8;

FIG. 15 is a perspective view on the front side and left hand side of a compressor in accordance with an embodiment of the present invention;

FIG. 16 is a front view of the compressor of FIG. 15;

FIG. 17 is a rear view of the compressor of FIG. 15;

FIG. 18 is a top view of the compressor of FIG. 15;

(Continued)

FIG. 19 is a bottom view of the compressor of FIG. 15;
 FIG. 20 is a left hand side view of the of the compressor of FIG. 15;

FIG. 21 is a right hand side view of the compressor of FIG. 15;

FIG. 22 is a perspective view on the front side and left hand side of a compressor in accordance with an embodiment of the present invention that is the same as the embodiment of FIG. 15, other than this embodiment additionally includes color features:

FIG. 23 is a front view of the compressor of FIG. 8;

FIG. 24 is a rear view of the compressor of FIG. 8;

FIG. 25 is a top view of the compressor of FIG. 8;

FIG. 26 is a bottom view of the compressor of FIG. 8;

FIG. 27 is a left hand side view of the of the compressor of FIG. 8; and,

FIG. 28 is a right hand side view of the compressor of FIG. 8.

The broken lines and ghosted regions in the drawings depict portions of the compressor that form no part of the claimed design.
